UNITED STATES PATENT OFFICE

2,580,196

LATCH BOLT HOLDBACK

Walter R. Schlage, deceased, late of Burlingame, Calif., by Anna Schlage, executrix, Burlingame, Calif., assignor to Schlage Lock Company, San Francisco, Calif., a corporation of California

Application April 12, 1947, Serial No. 741,039

10 Claims. (Cl. 292—169)

1

This invention relates to a door lock of the night latch type, and especially to a latch bolt hold back mechanism whereby the latch bolt of a night latch when retracted is automatically held in the retracted position until it is manually released.

A night latch is generally applied as a supplement to a door already having a knob actuated latch without key or other locking means. To open a door thus equipped, it is necessary to insert a key in the night latch and to rotate it with one hand in order to retract the supplementary latch bolt, and, while holding that latch bolt so retracted, simultaneously to grasp and rotate the door knob also to retract the regular latch bolt of the door. This requires the use of both hands and is awkward particularly if a person has one arm full of bundles or is otherwise handicapped.

The object of the present invention is generally to improve and simplify the construction and operation of locking mechanisms of the character described; and particularly to provide a lock of this character with a latch bolt hold back mechanism whereby when a key is inserted and rotated to retract the latch bolt, the latch bolt will be automatically held in retracted position until manually released. This permits the key hand to be transferred to the door knob to rotate it and open the door, so that only one hand is required.

A door lock of the night latch type equipped with a hold back mechanism of the character described is shown by way of illustration in the accompanying drawings, in which:

Figure 1 is a vertical longitudinal cross-section taken on lines I—I of Figure 2, showing the latch bolt and latch bolt housing for the most part in side elevation;

Figure 2 is a vertical transverse cross-section taken on lines II—II of Figure 1, showing the cylinder housing and spindle bar in side elevation;

Figure 3 is a view similar to Figure 2, said view showing the thumb turn at right angles to that shown in Figure 2;

Figure 4 is a perspective view of the latch unit;

Figure 5 is a perspective of the cylinder housing, the anchor bolts and spindle bar;

Figure 6 is a perspective view of the inside turn unit and latch unit hold back;

Figure 7 is an enlarged perspective view of the hold back unit escutcheon plate and spindle bearing;

Figure 8 is an enlarged perspective view of the hold back turn knob and spindle;

2

Figure 9 is an enlarged perspective view of the hold back dogs and push button;

Figure 10 is an enlarged perspective view of the dogging spring;

Figure 11 is an enlarged perspective view of the hold back driver cap; and

Figure 12 is a perspective view of the unit shown in Figure 6 but looking at the other end thereof.

A night latch of the character or type here shown comprises a latch bolt unit A (see Figure 4) which is provided with a latch bolt 2. A spindle 3 in the form of a bar extends through a crank arm 4. This crank arm carries a crank pin 5 which engages a notch 6 formed in a retractor bar. Whenever the spindle bar 3 is rotated, the crank arm 4 rotates with it and as the crank pin extends into the notch 6 of the retractor bar, it will pull said bar rearwardly to the dotted line position 7a (see Figure 1). The latch bolt 2 is secured to the retractor bar, and is simultaneously retracted against the urgency of a spring 8 of the customary kind.

The spindle bar 3 may be rotated from the outer side of the door by insertion and rotation of a key in the unit B (see Figure 5), or the spindle bar 3 may be rotated from the inner side of the door by a knob or turnpiece C (see Figures 6 and 12).

Regardless of whether the spindle bar is rotated from the outer side or the inner side of the door, the latch bolt will be retracted, and the important feature of the present invention is to provide a hold back or dogging mechanism which will automatically retain the latch bolt in its retracted position against the urgency of the spring 8 until it is manually released.

The hold back or dogging mechanism includes a base plate 15 carrying an escutcheon cap 16. The base plate 15 has a planar depression 15a throughout a portion of its area and has two holes 17—17 formed therein through which anchor screws 17b—17b extend. The base plate has also a central opening 18 through which extends a tubular spindle 19 carrying the knob or turnpiece C. The central opening 18 is extended by two diametrically opposed slots defined by pairs of shoulders 20—20 or keepers.

The tubular spindle 19 has two longitudinal slots 21 formed on opposite sides and having enlargements 22 at the inner ends. Bendable lugs 23 are formed on the inner end of the tubular spindle by cutting slots 24 therein. A driver cap 25 is slid over and secured to the inner end of the tubular spindle by deformation of the lugs 23. The cap 25 has its end perforated or cut to

form two segmental shaped openings 23a to receive the tubular spindle between the enlargements 22 and beyond the lugs 23, and it has four lugs formed between the segmental openings arranged in pairs 25a—25a so as to form a vertical and a horizontal slot between them.

A dogging member 25b in the shape of a flat fork (see Figure 9) has a cylindrical push button 26 secured at one end. The dogging member has a pair of lugs 27 and a pair of radially extending lugs 28 or dogs. The inner ends of the lugs 27 extend through the horizontal slot formed between the lugs 25a—25a of the cap 25 and well beyond the same when the button 26 assumes the depressed position shown in Figure 2. When the button 26 is in its extended position as shown in Figure 3, the legs are still in engagement with the lug pairs 25a—25a. The spindle bar 3 extends through the vertical slot formed between the lug pairs 25a—25a and between the lugs 27 of the dogging member 25b. This makes a connection between the spindle bar 3 and the tubular spindle 19 for simultaneous rotation.

When the several parts shown in Figures 8 to 11 are assembled, the cap 25 fits over and engages the end of the tubular spindle 19 and is there secured by bending the lugs 23 outwardly. The spindle bar 3 extends into the key unit B and it also extends through the vertical slot formed between the lug pairs 25a—25a into the interior of the tubular spindle 19. The lugs 27 of the dogging member 25b mounted in the spindle 19 straddle the spindle bar 3 and the lugs 28 and are slidably disposed in the longitudinal slots 21. A spring 30 is interposed between the driver cap 25 and the dogs or lugs 28 and urges the dogs or lugs into engagement with the depression 15a in the base plate 15.

In the normal projected position of the latch bolt 2, the dogging lugs 28 engage the depressed surface 15a and are in a position at right angles to the keepers or shoulders 20—20. When the spindle bar 3 is rotated either by a key or the turnpiece C, the lugs 28 revolve into alignment with the slots between the keeper shoulders 20. The spring 30 forces the dogging member 25b as a whole outwardly in the tubular spindle 19 into a position in which the dogs 28 rest between the shoulders or keepers 20—20 and against the ends of the longitudinally extending slots 21. When the dogging member 25b moves outwardly, the button 26 is carried with it into an extended position with relation to the knob or turnpiece C as shown in Figure 3. The projecting button 26 affords a visual indication of the then necessary position of the latch bolt and of the dogging member.

Whenever the dogging lugs 28 are out of the slots between the shoulders 20 and are in engagement with the depressed surface 15a of the base plate 15, the spindle bar 3 is moved into its normal locked position as the latch bolt is urged into its normal projected position by the spring 8. Whenever the spindle bar 3 is rotated either by the key mechanism B or the turnpiece C, the dogging lugs 28 register with the slots formed between the keeper shoulders 20—20 and the dogging member 25b then moves longitudinally due to the pressure of the spring 30 to enter between and engage the keeper shoulders and at the same time to extend the push button 26 into the position shown in Figure 3. Thus, when the push button 26 is extended as shown in Figure 3, it visibly indicates that the latch bolt of the night latch is retracted and that it is being held in

retracted position by the dogging members 25. The operation of dogging or holding the latch bolt when retracted against the spring 8 is accordingly automatic. A person who has used a key or who has rotated the turnpiece C can use the same hand to rotate the knob of the door lock to open the door. The latch bolt will remain in the retracted position until it is manually released. Release is accomplished by pressing the push button 26 to assume the position shown in Figure 2. This brings the dogs 28 out from between the keeper shoulders 20—20 so as to permit the spring 8 to project the latch bolt 2 and rotate the turnpiece C and the spindle 19 to a point so that the dogs 28 engage the depressed surface 15a of the base plate 15.

The hold back or dogging mechanism here shown is applicable to several types of night latches, see for instance patents of Walter R. Schlage, Nos. 1,829,814; 1,846,364; 1,876,080 and others. All of these patents explain how the individual units of the night latch are constructed and function and how they are assembled when placed in a door. While certain features of the hold back or dogging mechanism have been more or less specifically described and illustrated, it should be understood that changes may be resorted to within the scope of the appended claims.

Having thus described the invention, what is claimed and desired to secure by Letters Patent is:

1. In a door lock, a latch bolt, rotatable means for retracting the latch bolt, means for automatically dogging the rotatable member when the latch bolt is in retracted position to retain the latch bolt in the retracted position, and manually actuated means movable independently of and carried by the rotatable means for releasing the dogging means to release the latch bolt.
2. In a door lock, a latch bolt, a rotatable spindle, means actuated by rotation of the spindle for retracting the latch bolt, a dogging member automatically holding the spindle against rotation and so holding the latch bolt against projection when the latch bolt is in retracted position, and manually actuated means movable independently of said spindle for releasing the dogging member to release the spindle for rotation and for projection of the latch bolt.
3. In a door lock, a latch bolt, a rotatable spindle, means actuated by rotation of the spindle for retracting the latch bolt, a dogging member automatically holding the spindle against rotation and the latch bolt against projection when the latch bolt is in retracted position, a push button projecting from one end of the spindle when the latch bolt is held in the retracted position, and means actuated by depression of the push button for disengaging the dogging member to release the spindle and for projection of the latch bolt.
4. In a door lock a latch bolt, a rotatable spindle, means actuated by rotation of the spindle for retracting the latch bolt, a dogging member automatically holding the spindle against rotation and the latch bolt against projection when the latch bolt is in retracted position, a push button projecting from one end of the spindle when the latch bolt is held in the retracted position, means actuated by depression of the push button for disengaging the dogging member, and spring actuated means for projecting the latch bolt when the dogging member is disengaged.
5. In a door lock, a latch bolt, a rotatable spin-

dle, means actuated by rotation of the spindle for retracting the latch bolt, a dogging member automatically holding the spindle against rotation and the latch bolt against projection when the latch bolt is in retracted position, and means automatically moved into a position visibly projecting from one end of the spindle when the latch bolt is held in retracted position.

6. In a door lock, a latch bolt, a rotatable spindle, means actuated by rotation of the spindle for retracting the latch bolt, a dogging member automatically holding the spindle against rotation and the latch bolt against projection when the latch bolt is in retracted position, and means projecting from one end of the spindle and visibly indicating that the latch bolt is held in retracted position, said visible means being operable to disengage the dogging member and so to release the latch bolt.

7. In a door lock of the character described, a housing, a latch bolt, a spring tending to move the latch bolt into projected position, a spindle journaled in the housing, means actuated by rotation of the spindle for moving the latch bolt into retracted position, a dogging member rotatable with and slideable longitudinally in the spindle, a stationary keeper to receive the dogging member only when the latch bolt is in retracted position, a spring tending to move the dogging member into engagement with the keeper, and a push button carried by the dogging member and projecting from one end of the spindle when the dogging member is in engagement with the keeper.

8. In a door lock, a latch bolt, a spring for urging said latch bolt into projected position, a spindle, means actuated by rotation of the spindle for moving the latch bolt into retracted position and compressing said spring, a spring-compressed retainer for holding the latch bolt in retracted position only, and a manual button carried by the spindle for withdrawing the spring-compressed retainer and releasing the latch bolt for

movement into projected position under urgency of said spring.

5. A latch bolt hold back comprising a housing, a latch bolt movable between projected and retracted positions in said housing, a spring urging said latch bolt into projected position, a base plate stationary with respect to said housing, a hollow spindle rotatable in said base plate and engaging said latch bolt, a dogging member withdrawn and keyed to said spindle and projecting therefrom to rotate with said spindle relative to said base plate, means holding said dogging member against rotation with respect to said base plate only when said spindle is in a rotated position corresponding to the retracted position of said latch bolt, and a manual button for releasing said dogging member from said holding means.

10. A latch bolt hold back comprising a spring, a base plate, a spindle rotatable in said base plate between a first position corresponding to a de-energized position of said spring and a second position corresponding to an energized position of said spring, a dogging member keyed to said spindle and rotatable therewith, means for interlocking said dogging member and said base plate only in said second position of said spindle to hold said spring in energized position, and a manual button carried by said spindle for disengaging said interlocking means and releasing said spring to deenergized position.

30 ANNA SCHLAGE,
*Executrix of the Estate of Walter R. Schlage,
Deceased.*
